UNITED STATES PATENT OFFICE.

EMIL TAUSSIG, OF NEW YORK, N. Y.

DESIGN FOR A CASING FOR DISINFECTING APPARATUS.

SPECIFICATION forming part of Design No. 33,633, dated December 4, 1900.

Application filed November 10, 1900. Serial No. 36,134. Term of patent 7 years.

To all whom it may concern:

Be it known that I, EMIL TAUSSIG, a citizen of the United States, and a resident of the borough of Manhattan, in the city and State of New York, have invented and produced a new and original Design for a Casing for Disinfecting Apparatus, of which the following is a specification.

The leading feature of my design consists in a casing for disinfecting apparatus which comprises a cylindrical body portion provided with rounded ends, the said body portion having an annular band of perforations therein.

In the accompanying drawings, Figure 1 represents the casing in side elevation, and Fig. 2 represents the same in end elevation.

The cylindrical body portion of the casing is denoted by A and its rounded ends by B and C. The annular band of perforations in the cylindrical body portion A is denoted by a. 20

What I claim is—

The design for a casing for disinfecting apparatus, substantially as herein described.

In testimony that I claim the foregoing as my invention I have signed my name, in presence of two witnesses, this 17th day of October, 1900. 25

EMIL TAUSSIG.
